Fig. 1

The dominant features of my design reside in the full line portions of the drawing.

I claim:

The ornamental design of an illuminable changeable advertising exhibitor, as shown and described.
